DESIGN FOR A GLOVE

Frank J. Kaufmann, Tribes Hill, N. Y.

Application January 23, 1937, Serial No. 67,256

Term of patent 3½ years

To all whom it may concern:

Be it known that I, Frank J. Kaufmann, a citizen of the United States of America, residing in Tribes Hill, county of Montgomery, and State of New York, have invented a new, original, and ornamental Design for a Glove, of which the following is a specification, reference being had to the accompanying drawing, forming part hereof, wherein,

I claim:

The ornamental design for a glove, substantially as shown.

FRANK J. KAUFMANN.
